UNITED STATES PATENT OFFICE.

MILTON M. ADLER, OF NEWARK, NEW JERSEY.

DESIGN FOR A BOX.

Application filed April 17, 1923. Serial No. 5,839. Term of patent 7 years.

To all whom it may concern:

Be it known that I, MILTON M. ADLER, a citizen of the United States, residing at Newark, in the county of Essex and State of New Jersey, have invented a new, original, and ornamental Design for a Box, of which the following is a specification, reference being had to the accompanying drawing, forming part thereof.

In the drawing, Figure 1 is a side elevation, Figure 2 is a top or plan view, Figure 3 is an end elevation of a box, and Figure 4 is a perspective view of the same, showing my new design. Figure 2 and Figure 3 are for the purpose of showing Figure 4 in enlarged detail.

I claim:

The ornamental design for a box, as shown.

MILTON M. ADLER.
